UNITED STATES PATENT OFFICE.

DAVID JOHN SCOTT, OF PLAINFIELD, NEW JERSEY, ASSIGNOR TO ISABELLA SCOTT AND DAVID J. SCOTT, EXECUTORS OF THE ESTATE OF WALTER SCOTT, DECEASED.

OFFSET PERFECTING-PRESS.

1,282,642.

Specification of Letters Patent. Patented Oct. 22, 1918.

Original application filed April 2, 1915, Serial No. 18,639. Divided and this application filed September 29, 1916. Serial No. 122,835.

To all whom it may concern:

Be it known that I, DAVID J. SCOTT, a citizen of the United States, and a resident of Plainfield, in the county of Union and 5 State of New Jersey, have invented certain new and useful Improvements in Offset Perfecting-Presses, of which the following is a specification.

The present invention relates generally to 10 offset perfecting presses and has more particularly reference to the general arrangement of the printing units and elements composing the same.

The present application is a division of 15 one filed on April 2, 1915, Serial No. 18,639 and has for its main object the production of a machine in which both sides of the sheet are printed by the offset process and without the omission of elements necessary to produce 20 high class results; and in which the arrangement of cylinders is such that all the working parts will be completely accessible. Another object of the invention is to provide 25 means for conveniently controlling the various instrumentalities that make up the press.

Accordingly, the invention consists in the features of construction, combination of parts and arrangement of elements disclosed 30 in several preferred forms in the accompanying drawings. However, changes may be made in the particular forms disclosed herein without departing from the legitimate and intended scope of the invention.

35 In the drawings:

Figure 1 is a side elevation, largely in diagrammatic form, showing a sheet fed press embodying the invention.

Fig. 2 is a side elevation in diagrammatic 40 form, of a modification of the invention.

Similar characters of reference indicate corresponding parts in the several views.

The machine consists of two units, one 45 unit comprising the impression cylinder E, the transfer or blanket cylinder C and the form-carrying cylinder A, the other unit comprising the impression cylinder F, the transfer or blanket cylinder D and the form-carrying cylinder B. The form-carrying 50 and transfer cylinders of each unit are arranged one above the other in such manner as to form an exposed operating side for the machine, and the units are so grouped that the exposed operating side is outermost.

The impression cylinders of the two units 55 are located innermost of the machine and in contact with each other. In one unit the form-carrying cylinder A is at the upper end of the unit and the impression cylinder E at the lower end of the unit, while in the 60 other unit the form-carrying cylinder is at the lower end of the unit and the impression cylinder F is at the upper end of the unit.

Associated with the form-carrying cylinders 65 is the usual inking mechanism O and, when the character of the work requires it, the dampening mechanism N may be employed. In the present instance, the dampening mechanism N of one unit is located 70 non-adjacent to the operating side of its unit and above the impression cylinders, while the other dampening mechanism N is located on the operating side of the unit. Located adjacent to the operating side of 75 one unit and spaced therefrom so as to afford a gang-way or platform H is a source of supply of paper I, shown in Fig. 1 as a pile of paper and in Fig. 2 as a roll of paper. In Fig. 1, the sheets are fed over the feed-board J to the first impression cylinder E, and then to the second impression cylinder F, while in Fig. 2 the web is carried to the cutting cylinders M, which may be of the form known as all size rotary cutters, and 80 thence over the sheet path M' to feeding cylinder M², after which the paper passes to the first impression cylinder E and then to the second impression cylinder F.

A delivery mechanism is located under one 90 unit and substantially below both impression cylinders and adjacent to the inner side of the other unit. In the form shown in Fig. 1, this delivery is shown as a flat delivery K, while in Fig. 2 the delivery consists of the folding cylinders M³ and M⁴, which in turn deposit the folded sheets on the rotary delivery L² which feeds them to apron L'. A gang-way or platform G is in both instances located on the outside of the 100 delivery.

To prevent the printed side of the sheet from smutting the surface of the second impression cylinder, an anti-smutting device 37 is provided which engages with the 105 surface of the second impression cylinder and is interposed intermediate the delivery mechanism and the first impression cyl-

inner; or, to state it differently, the anti-smutting device is located substantially under the two impression cylinders and is in contact with the second impression cylinder.

5 Suitable means are provided for separating the cylinders so as to render them accessible. The two transfer or blanket cylinders C and D are mounted in sliding boxes 54 in a well-known manner and are so arranged 10 that when the throw-off mechanism is connected by handles 39 and 37', they will be moved outwardly of the exposed operating sides of the machine and away from their companion cylinders. Suitable means are 15 also provided for separating the two impression cylinders by mounting one or both of them in similar sliding boxes 54 controlled from the handles 14. If desired several cylinders may be tripped or thrown off in unison. Thus in Fig. 1 a connecting rod 120, 20 disconnectible by means of hook 36, connects handles 39 and 37' of the two transfer cylinders.

The dampening mechanisms N, if employed, may be withdrawn by means of handle 34 so as to bring them out of contact with the form-carrying cylinders. Similarly the anti-smutting device 37 may be moved out of contact with impression cylinder F by 30 means of operating handle 50.

What is claimed, is:

1. A rotary offset perfecting machine comprising: two units printing from positive forms on opposite sides of impression receiving material, each unit consisting of a form-carrying, a transfer and an impression cylinder, the form-carrying and transfer cylinders of one unit being arranged in a vertical column with the form-carrying cylinder 35 uppermost and the impression cylinder being arranged out of line with the other cylinders and lowermost to form an exposed operating side for the unit, the form-carrying and transfer cylinders of the other unit being arranged in a vertical column with the form-carrying cylinder 40 uppermost and the impression cylinder being arranged out of line with the other cylinders and lowermost to form an exposed operating side for the unit, the form-carrying and transfer cylinders of the other unit being arranged in a vertical column with the form-carrying cylinder lowermost and the impression cylinder being arranged out of line with the other cylinders and uppermost to form an exposed operating side, the units 45 being grouped with their operating sides uppermost and with the impression cylinders adjacent each other.

50 2. A rotary offset perfecting machine comprising: two units printing from positive

forms on opposite sides of impression receiving material, each unit consisting of a form-carrying, a transfer and an impression cylinder, the form-carrying and transfer cylinders of one unit being arranged in a vertical column with the form-carrying cylinder 55 uppermost and the impression cylinder being arranged out of line with the other cylinders and lowermost to form an exposed operating side for the unit, the form-carrying and transfer cylinders of the other unit 60 being arranged in a vertical column with the form-carrying cylinder lowermost and the impression cylinder being arranged out of line with the other cylinders and uppermost to form an exposed operating side, the units 65 being grouped with their operating sides outermost and with the impression cylinders adjacent each other, and means for throwing the transfer cylinders outwardly with respect to the operating sides of the machine. 70

3. A rotary offset perfecting machine comprising: two units printing from positive forms on opposite sides of impression receiving material, each unit consisting of a form-carrying, a transfer and an impression cylinder, the form-carrying and transfer cylinders of one unit being arranged in a vertical column with the form-carrying cylinder 75 lowermost and the impression cylinder being arranged out of line with the other cylinders and uppermost to form an exposed operating side, the units 80 being grouped with their operating sides outermost and with the impression cylinders adjacent each other, a feeding cylinder arranged adjacent to the impression cylinder of one unit, and a delivery cylinder adjacent to the impression cylinder of the other unit. 85

90 Signed at Plainfield, in the county of Union and State of New Jersey, this 27 day of September, A. D. 1916.

100 DAVID JOHN SCOTT.
